UNITED STATES PATENT OFFICE.

AUGUST VON PARSEVAL, OF CHARLOTTENBURG, GERMANY.

CONTROLLING DEVICE FOR AIRSHIPS.

970,262.

Specification of Letters Patent. Patented Sept. 13, 1910.

Application filed April 6, 1908. Serial No. 425,428.

To all whom it may concern:

Be it known that I, AUGUST VON PARSEVAL, a subject of the King of Bavaria, residing at Charlottenburg, Germany, have invented 5 certain new and useful Improvements in Controlling Devices for Airships, of which the following is a specification.

My invention relates to air ships especially to those of the non-rigid type and has 10 for its object to provide such air-ships with an arrangement by means of which the inclined position thereof can be regulated.

The invention is to be applied to long non-rigid air-ships provided with two air bags 15 so that the inclined position of the air ship can be regulated by driving air into one air bag and allowing air to escape simultaneously from the other bag.

According to my invention I provide the 20 air bags and the necessary air conduits and valve mechanism belonging thereto in such a manner that the air bags are made dependent upon one another and upon the gas content of the balloon. For this purpose the 25 air conduit, leading from a centrifugal fan or other suitable apparatus for supplying air, is provided with an inlet and an outlet valve which are so arranged that when an inlet valve is opened the corresponding outlet 30 valve is closed while the outlet valve is given free play when the inlet valve is closed. If the inclined position of the air ship is to be changed, air is blown into one of the 35 air bags. On opening the inlet valve for this purpose the corresponding outlet valve is closed. The increase of air pressure in one of the bags, and the increase in volume thereby, effects an increase of gas pressure in the air ship which drives the air from the 40 second air bag of which the outlet valve is not closed. The connection between the inlet valves and the corresponding outlet valves is such that the outlet valve is opened and closed when the corresponding inlet valve is 45 entirely opened whereas when the inlet valve is only partially opened it can work freely. The outlet valves act as automatic safety valves in that they allow the air to escape when it reaches a certain pressure.

50 My invention will be more clearly understood by referring to the accompanying drawing in which similar references indicate the same parts.

Figure 1 shows diagrammatically the 55 whole air ship, the air ship being cut along

its longitudinal axis. Figs. 2, 3, 4, 5, 6 show various constructional forms of valves.

In Fig. 1, 1 is the bag of the air ship within which are mounted two air bags 2. The air bags are connected by means of air tubes 3 to a central part 4 which is supplied with air from a fan or other suitable air supplying apparatus 5. The fan is advantageously carried in the car (not shown) of the air ship. In the central part 4 are provided the 60 inlet and outlet valves for the air bags 2, an inlet valve 6 and an outlet valve 7 being provided for each bag. In Fig. 1 simple dampers are shown as inlet valves and spring operated plates as outlet valves. The outlet 65 valves are of such construction that when the air reaches a certain pressure it is permitted to escape from the air bags 2. The inlet valves 6 can be opened and closed by any suitable gear and operate the outlet 70 valves as hereinafter described.

The connection between the inlet and outlet valves and the arrangement for operating the inlet valves is shown in Figs. 2-6. In Fig. 2 each part of the center piece 4 is provided with an inlet and an outlet valve. The inlet valve (not shown) which is in the form of a rotatable plate is mounted upon the axis 8 on the end of which projecting beyond the casing, is mounted a crank 9. To 80 the crank 9 is connected a cord 10 operated by the driver of the air ship. Each inlet valve is provided with a cord 10. To the plate of the outlet valve 7 is attached one arm of a bell crank lever 11 which is pivotally mounted in a bracket 12 and has its other arm connected to the cord 10 by a cord 13. It will be seen from the drawing that when the cord 10 is pulled the inlet and outlet valves are operated simultaneously the 85 cord 13 being of such a length that the outlet valve is not moved until the inlet valve is almost completely opened. When this is the case and the inlet valve is moved further until it is completely open then the outlet 90 valve is closed and remains closed as long as the inlet valve remains open. In Fig. 3 such a construction is shown in section. Within the center piece 4 is mounted upon an axis 8 a rotatable plate 6 which constitutes the inlet valve, to which is connected a spring which tends to bring the valve back into its closed position. To the end of the axis 8 outside the casing is fixed a crank 9 to which is attached the cord 10. The out- 100 105 110

let valve is fixed to a rod 15 which is guided in a bearing 16 provided on the valve seat. A spring 18 tends to keep the valve closed and thus forms a load upon the valve 7 which when the air is at a certain pressure automatically opens and allows the air to escape. The upper end of the rod 15 is bent at 19 at right angles and projects within reach of the rotatable plate 6 so that this 10 when almost entirely open, raises and closes the valve 7 and when completely open locks the latter in the closed position.

In the constructional form illustrated in Fig. 4 the inlet and outlet valves are co-axially disposed and are formed as plate valves. 19 is the inlet valve and 20 is the outlet valve. Each of the valves is mounted upon rods 21 which are guided in sleeves 22. The two rods 21 are connected together by a 20 chain. The outlet valve 20 is closed by the chain 23 and held in the closed position when the inlet valve is completely open. The movement of the inlet valve is in this case also effected by a cord 10 which is connected directly to the inlet valve. Also in the constructional form shown in Fig. 5 both the valves are in the form of spring operated plate valves 19 and 20 provided with spindles 21 guided in sleeves but at right 30 angles to one another. The valves are both operated by a bell crank lever 24 mounted upon an axis which outside the center piece 4 has mounted upon it a crank 9 to which the cord is attached. One arm of the bell crank 35 lever 24 rests against the spindle of the inlet valve 19 and pushes the valve 19 toward the left into the open position when the cord 10 is pulled downward. The other arm of the bell crank lever 24 abuts, when the valve 19 40 is nearly open, against the right-angular end 25 of the spindle of the outlet valve 20, thus closing the outlet valve and holding it in its closed position.

In Fig. 6 I have illustrated a constructional form in which the inlet valves are formed as rotary valves 26 for which purpose the center piece 4 is partly cylindrical. In Fig. 6 both of the inlet and outlet valves are shown, the inlet valve on the left side of the figure being closed and the outlet valve open and free, while on the right side of the figure the inlet valve is open and the outlet valve closed. The rotary valves 26 are mounted upon axes 27 provided outside the casing 4 with levers 28 to which the cords 10 are attached. Springs 29 are adapted to move the inlet valves into their closed positions. The outlet valves 30 are of the same construction as in Fig. 5. For operating 50 them there are mounted upon axes 31 levers 32 which rest against the right angular end of the valve spindles and in this manner operate the valves. The axes 31 are provided outside the casing with a lever 33 to which are attached cords 34 which are connected

to the cords 10. The cords 34 are of similar length to the cords 13 in Fig. 2 so that the outlet valves are not operated until the inlet valves are almost completely opened.

It will be understood that I do not wish 70 to limit myself to the particular forms of valves and their connections as illustrated as these may be varied without departing from the characteristic feature of the invention.

What I claim as my invention and desire to secure by Letters Patent is:—

1. In an aerostat or airship of the type described, two air bags connected together in such manner that when air is supplied to 80 one, the air contained in the other is permitted to escape, means for connecting together the two air bags, means for admitting air to one of the bags and permitting the air to escape from the other and means for 85 supplying air to the air bags substantially as described.

2. In an aerostat or air ship of the type described, two air bags connected together in such manner that when air is supplied 90 to one, the air contained in the other is permitted to escape, an air chamber connected to the air bags, means for connecting the said bags to the air chamber, means for admitting air to one of the bags and permitting the air to 95 escape from the other and means for supplying air to the air chamber substantially as described.

3. In an aerostat or air ship of the type described two air bags connected together 100 in such manner that when air is supplied to one, the air contained in the other is permitted to escape, an air chamber connected to the air bags, means for connecting the air bags alternately to the air chamber and 105 to the atmosphere, and means for supplying air to air chamber substantially as described.

4. In aerostats or air ships of the type described, two air bags, apparatus for supplying air, an air chamber in connection with the apparatus for supplying air, means for connecting the air bags alternately to the air chamber and to the atmosphere so that air may be supplied to one of the air bags 115 and the air contained in the other may escape substantially as described.

5. In aerostats or air ships of the type described, two air bags, apparatus for supplying air, an air chamber in connection with 120 the apparatus for supplying air, tubes for connecting the air bags to the air chamber, inlet valves disposed within the tubes, outlet valves disposed within the tubes and means for connecting the inlet valve of one 125 air bag to the outlet valve of the other airbag in such a manner that when air is being supplied to one bag, the air is permitted to escape from the other bag substantially as described.

6. In aerostats or airships of the type described, two air bags, apparatus for supplying air, an air chamber connected to the apparatus for supplying air, tubes for connecting the air chamber to the air bags, inlet valves disposed within the tubes, outlet valves disposed within the tubes, said outlet valves when the air reaches a certain pressure permitting the air to escape from the air bags into the atmosphere and automatically closing when the pressure is slightly decreased and means connecting the inlet

valve of one gas bag to the outlet valve of the other gas bag in such manner that when air is admitted into one air bag, the air contained in the other gas bag is permitted to escape substantially as described. 15

In witness whereof I have hereunto set my hand this 21st day of March, 1908.

AUGUST VON PARSEVAL.
